UNITED STATES PATENT OFFICE.

LOUIS BEGEMAN, OF CEDARFALLS, IOWA.

BATTERY.

SPECIFICATION forming part of Letters Patent No. 718,076, dated January 13, 1903.

Application filed January 7, 1902. Serial No. 88,753. (No model.)

To all whom it may concern:

Be it known that I, LOUIS BEGEMAN, a citizen of the United States, residing at Cedarfalls, in the county of Blackhawk and State 5 of Iowa, have invented a new and useful Battery, of which the following is a specification.

My invention relates to certain improvements in the construction of voltaic cells of the Lalande type, in which the positive-pole 10 electrode is formed of any suitable metal surrounded or covered by oxid of copper, which acts as a depolarizing agent, the negative-pole electrode being formed of zinc or other suitable material and caustic soda or caustic potash being employed as an exciting agent.

One of the objects of the invention is to materially reduce the cost of such cells by forming the insoluble electrode in cylindrical or elliptical shape and employing the same as a 20 receptacle for the exciting fluid.

A further object of the invention is to provide for the better support of the depolarizing agent.

A still further object of the invention is to 25 so construct the cell as to enable it to be used as a storage battery, the positive-pole electrode being employed as an anode and the cathode being formed by an amalgamated copper cylinder on which the zinc in solution 30 is deposited, the solution being regenerated and the reduced copper absorbing oxygen and returning to a state of oxid.

Further objects and advantages of my invention will be apparent from a reading of 35 the following description.

In the accompanying drawings, Figure 1 is a transverse sectional elevation of a voltaic cell constructed in accordance with my invention. Fig. 2 is a sectional plan view of the 40 same on the line 2 2, Fig. 1. Fig. 3 is an enlarged sectional detail illustrating more clearly the method of supporting the depolarizing agent. Fig. 4 is a view similar to Fig. 1, illustrating an amalgamated cathode inserted in place of the soluble electrode when 45 the cell is being regenerated. Fig. 5 is a sectional plan view of the same on the line 5 5 of Fig. 4. Fig. 6 is an enlarged sectional detail of a portion of the cathode.

Similar numerals of reference are employed 50 to indicate corresponding parts throughout the several views.

10 indicates a containing vessel, which may be formed of any suitable metal—such as tin, copper, or iron—and constitutes the insoluble 55 or positive-pole electrode. In order to increase the area of the electrode, the vessel may be corrugated, the corrugations serving also to better support the depolarizing agent 11, which, as usual, is formed of copper oxid. 60 When the vessel is formed of tin or other metal and has soldered seams, the seams are coated with a paste formed of graphite, gutta-percha, and paraffin in order to protect them from the action of the electrolyte.

The vessel is lined with wire gauze or netting, as indicated at 12, and the copper oxid in the form of a paste is forced through the mesh into contact with the inner surface of the vessel. To prevent disintegrated particles of the oxid from falling to the bottom of the vessel, I employ a shield or cover 13, formed of muslin or some similar material which will not interfere with the passage of the electrolyte, and this material is supported in place by an inner lining 14, also formed of wire gauze or netting, the gauze or netting being preferably of elastic metal, which may be sprung into place and render unnecessary any auxiliary fastening devices.

Where the positive-pole electrode is formed of iron it is preferably copper-plated in order to lessen the initial internal resistance of the cell.

The negative-pole electrode is formed of 85 zinc or other suitable material supported by a cap or cover 16 and provided with a binding-post 17 of any suitable character. The binding-post 18 of the positive-pole electrode is provided with a threaded end 19, extending 90 through the upper portion of the receptacle and serving to hold the cap or cover in place.

When an exciting fluid, such as a solution of caustic potash or caustic soda, is placed in the cell and the circuit is established, the 95 zinc is attacked and is dissolved or converted into an oxid, while the oxid of copper is gradually reduced to a metallic state. When this

occurs, the cell is exhausted and the oxid must be renewed before the cell can be again used.

The bottom of the cell is covered with a 5 layer of copper oxid, as shown in the drawings, or with a coating of cement of the character hereinbefore described. When the cell is to be used as a secondary or storage battery, I prefer to have the bottom covered with 10 cement in order to seal the bottom of the can effectively and prevent any of the oxid of copper from leaking out under the shield.

In order to recover the zinc precipitate and to transform the metallic copper to a state of 15 oxid, I remove the zinc electrode and place 20 in the solution a cathode of the construction illustrated in Figs. 4, 5, and 6. The cathode comprises a copper body 18, preferably of cylindrical form and provided with one or more 25 terminals 19 for connection to a suitable binding-post. The copper cylinder is surrounded by brass or copper gauze 20 of fine mesh, and the whole is thoroughly amalgamated with mercury. On the passage of a current from 30 the positive-pole element, which now forms the anode, to the copper cathode the zinc in the solution is deposited on the said cathode and is held by the fine gauze, the gauze forming a much better supporting-surface than 35 would the solid zinc electrode. The anode will absorb oxygen and will be reduced or returned to a state of oxid, the solution being cleared or regenerated and again in condition to receive the zinc electrode and set up a current from the chemical reaction which takes 40 place when the charging-current is cut off. In some cases this cathode may be retained in the cell and used as the soluble electrode until the deposited zinc has been dissolved 45 or precipitated; but usually I prefer to employ the usual zinc electrode.

While the construction herein described and illustrated in the accompanying drawings is the preferred form of the device, it is 45 obvious that many changes in the form, pro-

portions, size, and minor details of the structure may be made without departing from the spirit or sacrificing any of the advantages of my invention.

Having thus described my invention, what 50 I claim is—

1. An electric battery comprising in combination, a containing vessel adapted to form the positive-pole electrode, a depolarizing agent forming a lining for said cell, a lining 55 of wire gauze or netting in the interstices or meshes of which said depolarizing agent is partially embedded and supported, a protecting-shield covering said gauze or netting, and a negative-pole electrode situated within said 60 vessel.

2. The combination in an electric battery, of the containing vessel forming an electrode, wire gauze or netting arranged within said vessel and forming a support for a copper- 65 oxid depolarizing agent, a protecting-shield covering said gauze or netting, and an elastic sheet of gauze or netting adapted to support said shield.

3. The combination in an electric battery, 70 of the containing vessel formed of metal and having a protective lining for its seams or joints, an inner lining of wire gauze or netting and a copper-oxid depolarizing agent supported thereby. 75

4. The combination in an electric battery, of the corrugated metallic vessel forming one element of the battery, an inner lining of wire gauze or netting, and a copper-oxid depolarizing agent supported by said wire gauze 80 or netting and by the corrugations of the vessel.

In testimony that I claim the foregoing as my own I have hereto affixed my signature in the presence of two witnesses.

LOUIS BEGEMAN.
